CLOTHES WRINGER

Simon E. Schroeder, Chicago, Ill., assignor to
Electric Household Utilities Corporation, Chi-
cago, Ill., a corporation of Illinois

Application December 13, 1935, Serial No. 54,285

28 Claims. (CL 68—253)

This invention relates to improvements in power-driven wringers, especially adapted for use in connection with washing machines.

One object of the invention is to provide a wringer of the pressure roll type, wherein the resetting of the rolls after release thereof may be accomplished with a minimum amount of effort.

A more specific object of the invention is to provide in a wringer having cooperating rolls operating under pressure and adapted to be released from pressure and separated when desired by the operator, especially in case of emergency, means automatically thrown into operation upon removal of the pressure for withdrawing or retracting one of said rolls from operative position to provide clearance for the other roll, thus eliminating the resistance ordinarily encountered in bringing the rolls back to operative position and reducing to a minimum the effort required in resetting the wringer.

Another object of the invention is to provide in a wringer, as set forth in the preceding paragraph, means actuated through movement of the usual lever for controlling the starting and stopping of the wringer for returning the retracted roll to cooperative position with respect to the other roll.

A still further object of the invention is to provide in a wringer of the roll type, having the rolls thereof held to the work under yielding pressure, manually actuated means for starting the operation of the wringer and simultaneously advancing one of the rolls toward the other to bring said rolls in pressure-exerting relation.

Yet another object of the invention is to provide a power-driven wringer comprising rolls operating under yielding pressure and arranged to be released from operative pressure-exerting relation with respect to each other when the occasion arises, wherein the power is automatically disconnected when the rolls are relieved from pressure, thereby stopping operation of the wringer rolls.

A further object of the invention is to provide in a power-driven wringer of the pressure roll type, having shiftable control lever means for operating a shiftable clutch means for connecting and disconnecting the power to start and stop rotation of the rolls, means normally held in inoperative condition by the pressure reacting between said rolls, which is automatically thrown into operation upon removal of said pressure to shift the control lever means to disengage said

clutch means and stop rotation of the wringer rolls.

Another object of the invention is to provide a wringer of the power-driven roll type of simple and rugged design, wherein substantially the entire main frame structure is in the form of a cantilever beam, which supports the whole wringer mechanism and thoroughly braces the frame structure.

Other objects of the invention will more clearly appear from the description and claims herein-after following.

In the drawings, forming a part of this specification,

Fig. 1 is a vertical sectional view of my improved wringer, corresponding substantially to the line 1—1 of Fig. 2, certain parts being shown in elevation and others being broken away.

Fig. 1a is a view similar to Fig. 1, on an enlarged scale, showing the mechanism at the lower central portion of said figure, said mechanism being broken away.

Fig. 1b is a vertical sectional view, corresponding substantially to the line 1b—1b of Fig. 1a.

Fig. 2 is a vertical sectional view, on an enlarged scale, corresponding substantially to the line 2—2 of Fig. 1, said view being partly broken away.

Fig. 3a is a view similar to Fig. 1, on an enlarged scale, showing the structure at the left-hand end of said figure.

Fig. 3b is a view similar to Fig. 1, on an enlarged scale, showing the structure at the right-hand end of said figure.

Figs. 4a and 4b are views respectively similar to Figs. 3a and 3b, showing the parts in different positions and illustrating the wringer rolls as engaged with an article being passed through the wringer.

Fig. 5 is a view similar to Fig. 4b, with the parts shown in another position, the wringer rolls being illustrated as released and the bottom roll of the wringer as returned to its lowered position.

Fig. 6 is a vertical sectional view, corresponding to the line 6—6 of Fig. 4b.

Fig. 7 is a detailed perspective view of certain lever mechanism shown in Figs. 1, 3b, 4b, 5, and 6.

Fig. 8 is a broken plan view of a portion of a certain channel beam member forming a part of the frame structure of my improved wringer.

Fig. 9 is a broken elevational view of a certain slide member or bar for anchoring the top roll of the wringer to the spring-tensioning means for pressing the rolls together.

Fig. 10 is a vertical sectional view, corresponding substantially to the line 10—10 of Fig. 3b.

Fig. 11 is a broken view similar to Fig. 10, showing the parts in a different position.

5 Fig. 12 is a view similar to Fig. 11, showing the parts in still another position.

Fig. 13 is a view similar to Fig. 1, showing the upper portion only of the wringer, the front wall of the top frame being entirely omitted in this 10 view to clearly disclose the locking and releasing mechanism for the top frame of the wringer.

Fig. 14 is a broken view similar to Fig. 13, on an enlarged scale.

Fig. 15 is a horizontal sectional view, corresponding substantially to the line 15—15 of Fig. 1.

Fig. 16 is a view similar to Fig. 15, showing the parts in a different position.

Fig. 17 is a top plan view of a certain slide member, which forms a part of the locking and 20 releasing mechanism shown in Figs. 13 to 16 inclusive.

In said drawings, A indicates the main or bottom frame, B the top or auxiliary frame, and C and D respectively the top and bottom rolls of 25 my improved wringer. The top and bottom rolls C and D are carried respectively by the top and bottom frames B and A in a manner hereinafter more fully described.

The main frame A comprises a channel beam 30 member 20 and hollow upstanding posts 21 and 22 at opposite sides of the frame fixed to the channel beam member 20. The channel beam member 20 is in the form of a heavy sheet metal stamping open at the bottom and having a horizontally disposed top wall 23, spaced vertical front and rear walls 24—24, and vertical side walls 25—25.

The posts 21 and 22 are also heavy sheet metal stampings. Each post has front and rear walls 40 26—26, an outer side wall 27, and an inner side wall 28. The front and rear walls 26—26 and the outer side wall 27 of each post at their lower ends overlap the front and rear walls 24—24 and the corresponding side wall 25 of the channel 45 beam member 20 and are fixed thereto in any well known manner. The inner side wall 28 of each post is formed by laterally inwardly bent right angular sections of the front and rear walls 26—26. The construction of this inner side wall 28 is most clearly illustrated in Figs. 15 and 16. As shown therein, the opposed vertical inner end edges of the two sections of said wall 28 are spaced apart to accommodate the shafts of the rolls C and D, as hereinafter more fully described.

50 A guard plate 29 is secured to the inner side of each post 21 and 22. Each guard plate 29 has a continuous flange 30 extending along opposite side edges and the bottom end edge thereof. The flanges 30—30 of the two guard plates 29—29 55 embrace opposite sides of the top and bottom rolls C and D and the lower side of the roll D, thereby directing the water inwardly to be received by a tilting drainboard 31 beneath the bottom roll D. Each guard plate 29 is centrally 60 slotted to accommodate the shafts of the wringer rolls C and D and has the opposite edge portions of the body of the plate at said slot bent into U form, as indicated at 32—32 in Figs. 15 and 16, and engaged over the inner edge portions of the 65 sections of the wall 28 of the corresponding post.

The post 21, which forms the head of the main frame A, has an opening 33 in the outer side wall 27 thereof, said opening being closed by a plate-like casting 34, which serves as a bearing support for the controlling lever or handle member

35 of the wringer, as hereinafter more fully described. The top of the post 21 is partly closed by a supporting and bracing plate 36, which fits between the front and rear walls 26—26 of the post 21 and abuts the outer side wall 27. As shown most clearly in Figs. 1, 3b, 4b and 5, the plate 36 is flanged upwardly, said flanged portions being secured to the front and rear walls 26—26 and the outer side wall 27 in any well known manner. The plate 36 and the top wall 23 of the channel beam member 20 have aligned openings 37—37, which accommodate a vertically disposed tubular sleeve 38. The sleeve 38 snugly fits these openings, which are flanged outwardly, and is fixed to the plate 36 and the beam 20 respectively. A bearing bracket 39 is fixed to the left-hand side of the sleeve 38, as viewed in Figs. 1, 3b, 4b, and 5. This bracket 39, together with the sleeve 38, serves as means for housing the driving gearing for the wringer, hereinafter more fully described. The sleeve 38 projects downwardly beyond the beam 20 and is adapted to telescope over the upper end portion of the usual vertically arranged hollow standard of a washing machine having a vertically disposed shaft therein operatively connected to and rotated by the driving elements of the washing machine in a well known manner. The shaft of the hollow standard extends upwardly beyond the standard and a considerable distance into the hollow tubular sleeve 38 and is coupled to the gearing of the wringer by a splined or similar connection. The top portion of such a shaft is indicated by 40 in Figs. 1, 3b, 4b, and 5, and is connected to the gearing of my improved wringer, as hereinafter more fully described.

A pair of castings 40—40 are secured to the front and rear of the main frame A and serve as fixed drainboard members. The tilting drainboard 31 is provided to direct the water from beneath the bottom roll D to either of the fixed drainboards of the castings 40—40. As shown in Figs. 1 and 2, the drainboard 31 is supported by pivots 42—42 at opposite ends mounted on the inner side walls 28—28 of the posts 21 and 22. Means (not shown) is provided for tilting the drainboard 31 in the proper direction in accordance with the direction of rotation of the rolls C and D, but this mechanism does not form any part of the present invention and, therefore, needs no further description. In this connection, it is pointed out that the structure of the main or bottom frame A is of exceedingly rigid design, the channel beam member 20 at the bottom of said frame forming a cantilever beam, which extends continuously from one side of the wringer to the other and forms an integral part of the head by which the wringer is supported on the vertical standard of the associated washing machine.

The frame B is preferably a heavy sheet metal stamping in the form of a channel member closed at opposite ends and open at the bottom. The frame B is telescoped over the upper ends of the posts 21 and 22 of the frame A, as most clearly shown in Figs. 1, 2, 6, and 10, and forms in effect a cap closing the top of the wringer. The frame B carries a pair of depending bearing struts 41—41, in which the top roll C is rotatably supported.

The main frame A also carries spring tension or yielding pressure means for the roll C of the frame B. This spring tension or pressure means comprises a leaf spring 42 and connecting slide bars or plates 43—43 anchored to opposite ends

of the leaf spring. The leaf spring 42 is disposed below the bottom roll D in the opening of the channel beam member 20, as clearly shown in Figs. 1, 1a, and 2. The leaf spring 42 is relatively thick at the center and tapered toward its opposite ends, and is supported at the central portion thereof in a clip 44, which is adjustably mounted on the channel beam member 20 of the frame A. As shown most clearly in Fig. 1b, the clip 44 is in the form of a relatively heavy plate having upstanding side portions 45-45 provided with in-turned lugs 46-46 and 46-46 at their upper ends overhanging the leaf spring 42. The clip 44 is adjustably connected to a supporting plate or brace 47, which is fixed to the front and rear walls 24-24 of the channel beam 20. An adjusting nut 48 cooperating with a screw 49 forms the adjustable connection between the plate 47 and the clip 44. As shown most clearly in Figs. 1, 1a, 20 and 1b, the screw 49 is headed at the upper end, said headed portion being anchored to the clip 44. The portion of the screw 49 which extends through the main body portion of the clip 44 is of angular cross section, thereby holding the screw against turning with respect to the clip. The nut 48, which has threaded engagement with the screw 49, is enlarged at the lower end so as to provide a head which is shouldered on the plate 47. As will be evident, when the nut 48 is turned, the clip 44 will be adjusted either upwardly or downwardly, depending upon the direction of rotation of the nut, thereby effecting corresponding adjustment of the leaf spring 42. The connecting slide bars 43-43 are located at opposite ends of the leaf spring 42, as clearly shown in Fig. 1, and have hooked lower ends 50-50, which are engaged beneath the extremities of said leaf spring. Each connecting slide bar 43 is limited in its downward movement by a set screw 51 threaded in the platelike section of a supporting bracket 52 fixed to the inner sides of the front and rear walls 24-24 of the channel beam member 20 at the corresponding side of the wringer. The set screw 51 engages the hooked end 50 of the bar 43 and serves as an adjustable stop or abutment for determining the lower limit of movement of said connecting bar 43. As most clearly shown in Fig. 9, each connecting slide bar 43 is slotted at the upper end portion thereof, as indicated at 53. The slot 53, which is closed at both ends, has the upper end thereof laterally enlarged, as indicated at 54, to accommodate the engaging end portion of a locking bar hereinafter more fully described. The upper end of each connecting slide bar 43 is bent outwardly, as indicated at 55, said outwardly bent portion being located immediately above the slot of the bar 43. The top wall of the widened portion 54 of the slot is inwardly beveled or inclined, as clearly shown in Figs. 1, 3a, 3b, 4a, 4b, and 5, to properly cooperate with the end of the locking bar hereinbefore referred to. The connecting slide bars 43-43 are guided in their movements by guide pins 56-56 fixed to the main frame A. The guide pin 56 for the connecting slide bar 43 at the right-hand side of the wringer, as viewed in Fig. 1, is fixed to the upstanding flange at the inner side of the plate 36 of the post 21 and is engaged within the slot 53 of the bar 43. The guide pin 56 of the connecting slide bar 43 at the left-hand side of the wringer, as viewed in Fig. 1, is directly secured to the outer side wall 27 of the post 22. As clearly shown in the drawings, the guide pins 56-56 are headed so as to prevent accidental dis-

engagement of the connecting slide bar 43-43 therefrom.

The top and bottom rolls C and D are of the usual rubber-surfaced type employed in power-driven wringers. Each roll is supported on a shaft 5 fixed thereto, which rotatably mounts the roll. The shaft of the top roll C is indicated by 57 and the shaft of the bottom roll D is indicated by 58. As clearly shown in Fig. 1, each roll shaft projects from opposite ends of the roll and is engaged in suitable bearing elements. A clip, in the form of a plate 150, is interposed between each guard plate 29 and the corresponding ends of the rolls C and D. Each plate 150 is provided with an opening 151 at the bottom portion thereof through which the corresponding end of the shaft 58 of the roll D extends. The upper portion of each plate 150 is slotted, as indicated at 152, to accommodate the corresponding end of the shaft 57 of the top roll C. The slot 152-152 of the plates 150-150 are open at the upper ends of the plates to permit insertion of the shaft 57 of the roll C and are of such a length as to permit vertical movement of the plates 150-150 with the roll D without interference by the shaft 57 of the roll C. The clips or plates 150 serve as abutments for taking the end thrust of the rolls C and D and hold the rolls against endwise displacement. The opposite ends of the shaft 57 of the top roll C are rotatably supported in the struts 41-41 carried by the frame B. The struts 41-41, which are in the form of castings, are disposed within the opening of the frame B between the front and rear walls thereof. As shown most clearly in Fig. 1, the struts 41-41 are mounted on the frame B so that they are located at opposite ends of the top roll C and respectively occupy the space between the inner wall of the post 21 and the corresponding connecting bar 43 and the space between the inner wall of the post 22 and the corresponding connecting bar 43. Each strut 41 is held against lateral displacement with respect to the frame A by oppositely projecting lugs 153-153 thereon, which bear on the front and rear walls 26-26 of this frame. At the upper ends, the struts 41-41 are held against lateral displacement with respect to the frame B by horizontally arranged plates 154-154 fixed to said upper ends and having downwardly bent extremities bearing on the inner sides of the front and rear walls of the frame B. Each strut 41 has an opening between the top and bottom ends thereof, which is provided with a bearing bushing 59 rotatably receiving and supporting the corresponding end of the shaft 57 of the roll C. The bottom end portion of each strut 41 is cut away, as indicated at 60 and as most clearly shown in Fig. 6, to provide clearance for the shaft and bearing member of the bottom roll D. The cut-away portion 60 is preferably of inverted V shape, but may be of any other suitable form so as to provide the proper clearance. The upper end portions of the bearing struts 41-41, which are located within the hollow portion of the top frame B, are horizontally slotted, as indicated at 61-61, to form supporting guideways for locking or latch bars 62-62 hereinafter more fully described, which locking or latch bars serve to lock the frame B and the top roll C carried thereby in operative position with respect to the bottom roll D of the wringer. The latch bars 62-62 are mounted on the frame B and serve to support the struts 41-41 on said frame. Each strut 41 also carries a combined guard and guide hook member 63 at the top end thereof. As most clearly shown in Figs. 1 and 6,

the guard and guide hook member 63 is formed on the plate 154, which is fixed to the strut, and includes a hook portion extending laterally from the strut and overhanging the upper end of the corresponding connecting slide bar 43. Each combined guard and guide hook member 63 has the plate portion 154 thereof overlying the slot 61 of the corresponding strut 41 and forming the top wall of the guideway for the locking bar 62. The combined guard and guide hook members 63—63 serve to properly align the upper ends of the connecting slide bars 43—43 with the locking bars 62—62 of the combined locking and latch means.

The combined locking and latch means for locking the frame B to the frame A is mounted on the frame B and is arranged so as to provide for quick and easy release thereof when desired by the operator, thereby effecting complete disengagement of the locking means and permitting lifting of the frame B and the top roll C carried thereby and entire removal of these parts from the wringer. The operation of the combined latch and locking means, which includes the bars 62—62, is controlled by a manually-actuated hand piece or slide 64 mounted in the frame B. As shown most clearly in Figs. 13 to 17 inclusive, the slide 64 is mounted for horizontal movement in guide openings or slots 65—65 provided in the front and rear walls respectively of the frame B. As shown in Figs. 2 and 15, the openings 65—65 are flanged inwardly around their edges so as to form ample guide surfaces. The slide 64 comprises a pair of hand pieces 66—66 at opposite sides thereof, a central longitudinally extending bar 67 parallel to the hand pieces 66—66, and transverse connecting plates 68—69 and 68—69 at opposite ends thereof secured to the hand pieces 66—66 and the central bar 67. Each hand piece 66 is in the form of a hollow channel-shaped member closed at opposite ends and open at the inner side. The plates of each pair 68—69 have their outer ends fixed to the top flanges or webs of the hand pieces 66—66 respectively. The inner ends of said pair of plates 68—69 are fixed to the corresponding end of the bar 67 by rivets or any other equivalent securing means. The pairs of plates 68—69 and 68—69 have upstanding stop lugs 70—70 at opposite sides of the slide 64, which are adapted to engage with the front and rear walls of the frame B to restrict lateral outward movement of the slide 64 with respect to said frame B. Each plate 68 of the slide 64 is provided with a set of cam faces 71—71, which are reversely inclined and are adapted to cooperate with a slide frame 72, as hereinafter pointed out.

The slide 72, as most clearly shown in Figs. 2, 14, and 17, is in the form of an arched plate or saddle member having a central opening 73 and depending guide feet 74—74 and 74—74 at opposite ends thereof, which are in the form of folded lugs bent from said plate. The feet 74—74 and 74—74 rest on the inturned top flanges of the slots or guide openings 65—65 of the frame B and serve to support and guide the saddle member 72 longitudinally of the frame B. The saddle member 72 has two spaced cam fingers 75—75 depending from the top wall thereof. Each cam finger 75 is in the form of a plate having a depending lug 76 thereon to which one end of a tension spring 77 is anchored. The opposite end of the spring 77 is anchored to a depending lug 78 on the plate 68 at the corresponding end of the slide 64. As will be seen, the cam fingers 75—75 of the sliding saddle 72 are thus held in yielding engagement with the cam faces 71—71 of said plates 68—69. In order to provide proper bearing faces on the cam fingers 75—75, these fingers are provided with reversely bent lips 79—79 at the lower ends thereof, the rounded surfaces of said lips directly engaging the cam faces 71—71 and 71—71 of the slide 64. The saddle 72 is further provided with a depending keeper member 80, which is in the form of an angularly disposed plate having a rounded lip 81 at the outer edge of the lower portion thereof, which is adapted to cooperate with a keeper-engaging finger or latch member 82. A supporting bracket 83 in the form of a bent elongated bar is fixed to the inner side of the top wall of the frame B and extends through the opening 73 of the saddle slide member 72. The supporting bracket 83 has a depending offset portion 84 on which the latch finger 82 is pivotally supported by means of a pivot screw or bolt 85. The bracket 83 is further provided with a horizontally disposed depending tongue 86 at the right-hand end thereof, as viewed in Fig. 13, this tongue being in a plane above the pivotal connection of the finger 82 with said bracket and serving as a support for a spring abutment plate 87, which is secured thereto. The shank portion of the finger 82, which is indicated by 88 and through which the pivot 85 extends, is in the form of a link member connecting the inner ends of the latch bars 62—62. As shown most clearly in Figs. 15 and 16, the engaging portion proper of the latch finger 82 extends at an angle to the shank portion 88 thereof and has a head 89 at the outer end thereof having a rounded end face and a nib 90 at one side thereof, which is adapted to hook over the keeper 80. At the left-hand end, as viewed in Figs. 15 and 16, the shank 88 of the finger 82 is pivotally connected to the inner end of the latch bar 62 by a pivot member 91. Near the opposite end, the shank 88 of the finger 82 is pivotally connected to the inner end of the other latch bar 62 by a pivot member 92. The two locking bars 62—62 are thus operatively connected by the shank 88 of the finger 82, said shank forming a connecting link. The finger 82 is normally yieldingly urged to the position shown in Fig. 15 by means of a spring 93 reacting between the spring abutment plate 87 and the shank 88 of the finger 82. The spring 93 is supported on an elongated pin 94, which has a head 95 at the left-hand end, as viewed in Figs. 15 and 16. The pin 94 extends through an opening in a right angular bent section 96 of the abutment plate 87, thus supporting the pin for sliding movement. The head end of the pin 94 is anchored to a laterally projecting lug 97 on the shank 88 of the finger 82 by means of a hooked end portion on said pin engaged within an opening provided in said lug. The spring 93 is of the compression type and bears at opposite ends respectively on the head 95 of the pin 94 and the abutment projection 96 of the plate 87. To limit the swinging movement of the finger 82 and arrest the movement of the locking or latch bars 62—62 in their disengaged position, as shown in Fig. 16, the bar 62 at the right-hand end of the wringer, as viewed in said figure, is provided with an upstanding stop pin 98, which is engaged by the nib 90 of said finger. To facilitate engagement and disengagement of the latch or locking bars 62—62 with the connecting slide bars 43—43 of the spring mechanism, the outer ends of the bars 62—62 are beveled as shown.

When the frame B is locked to the main frame A, the parts are substantially in the positions shown in Figs. 1, 2, 3a, 3b, and 15. At this time, the locking bars 62-62 are positively held in latching engagement with the connecting bars 43-43 of the spring mechanism by engagement of the latch finger 82 with the keeper 80 of the sliding saddle member 72. As will be evident, the springs 77-77 yieldingly maintain the saddle 10 72 in position with the keeper 80 interlocked with the finger 82. In the operation of the wringer, the bottom roll D is raised upwardly and forced against the top roll C, as hereinafter pointed out in detail. The pressure exerted by the roll D 15 against the roll C raises the latter, thereby raising the struts 41-41 and the connected parts of the frame B, together with the connecting bars 43-43, which are locked to the frame B by the latch or locking bars 62-62. The leaf spring 42 20 will thus be flexed by the upward pull of the connecting bars 43-43 thereon, placing the rolls C and D under yielding spring pressure. During the operation of the wringer, the rolls will be separated by the article being passed therebetween, thereby placing the leaf spring 42 under additional tension. To release the frame B together with its roll C in case of emergency or when it is found desirable to do so for any other reason, the operator pushes the slide 64 to either side of the position shown in Fig. 15, thereby camming the saddle member 72 to the right, as viewed in Fig. 15, and displacing the keeper 80 from the position shown in Fig. 15 to that shown in Fig. 16. The nib 90 of the latch finger 82 will thus be freed to permit swinging movement of said finger. Due to the forces reacting between the beveled outer ends of the latch bars 62-62 and the inclined abutment faces on the connecting bars 43-43, the locking bars 62-62 will be cammed inwardly until they are freed from the bars 43-43. Due to the pull produced by the tension of the spring 42, the connecting bars 43-43 will be pulled downwardly a sufficient distance to clear the ends of the bars 62-62 from the latch openings of the bars 43-43. As will be clear upon reference to Fig. 16, which shows the slide 64 displaced to one side, the locking bars 62-62 when forced inwardly free of the connecting bars 43-43 will 45 swing the finger 82 to a position where it engages the stop pin 98. During this action the spring 93 will be compressed, thus tending to force the finger 82 to return to the normal position shown in Fig. 15. In this connection, it is pointed out that after the saddle 72 has been actuated to release the keeper 80 from the finger 82 it will immediately be restored to the normal position shown in Fig. 15 due to the pull of the springs 77-77. In returning the finger 82 to the normal 50 position by the action of the spring 93, the latch bars 62-62 are forced yieldingly outwardly and ride up on the inclined upper ends of the bars 43-43, as shown most clearly in Fig. 5, until the finger 82 is again engaged with the keeper 80, as shown in Fig. 15. When the frame B has thus been unlocked from the frame A, the operator may entirely withdraw the frame B from the frame A. In replacing the frame B on the frame A and again locking the parts together, the operator forces the frame B downwardly onto the frame A, thereby causing the outer ends of the locking bars 62-62, which are held against inward movement by the latch finger 82, to engage the inclined upper end portions of the connecting bars 43-43 of the spring mechanism to force the bars apart. As the bars 62-62 are rigid at this time, the bars 43-43 will be forced apart as the former ride down the inclined portions of the latter. At the same time, the hook members 63-63 will be engaged over the upper 5 ends of said bars 43-43. When the frame B has been forced downwardly a sufficient distance to bring the engaging ends of the locking bars 62-62 in alignment with the locking openings of the connecting bars 43-43, the bars 62-62 10 will snap into the locking openings due to the inherent resiliency of the connecting bars 43-43. When the parts have thus been locked together, the hook members 63-63 effectively hold the upper ends of the bars 43-43 against spreading. 15 In this connection, it is pointed out that the releasing slide 64 is also automatically operated to unlock the frame B from the main frame A when the wringer rolls become jammed due to an article being wound about the top roll. When an 20 article is thus accidentally wound about the top roll, the same will engage the bar 67, thereby moving the slide laterally and, through lateral movement of the slide 64, releasing the latching mechanism, as hereinbefore described. 25

The bottom roll D, which is displaceable vertically to engage the roll C, has the opposite ends of the shaft 58 thereof rotatably journaled in bearing blocks 99-99. The bearing blocks 99-99 are open at the top and are lined with bushings 30 of semicircular cross section, in which the ends of the shaft 58 are directly supported. The projecting end of the shaft 58 at the right-hand side of the wringer, as viewed in Fig. 1, is provided with an extension of angular cross section to receive a coupling element 100 in the form of a sleeve to connect the shaft to the driving gear of the wringer, as hereinafter pointed out. The bearing blocks 99-99 are movably arranged below the struts 41-41 of the frame B. Each 35 block 99 is guided between the inner side wall 28 of the corresponding post and the connecting bar 43 at the same side of the wringer. Each block 99 is provided with a pair of oppositely extending lugs 155-155, which bear respectively on the inner sides of the front and rear walls 26-26 of the frame A and guide the block for vertical movement between said walls. The bearing blocks 99-99 are carried by movable supporting means through which the bearing blocks 99-99 40 are raised and lowered so as to effect raising and lowering of the bottom roll D to force the latter against the top roll C and withdraw the same therefrom. This movable supporting means includes a horizontally disposed slide bar 101 and 45 toggle links 102-102 connected to opposite ends of said bar 101. A cam-operated bell crank lever 103 connected to the right-hand end of the bar 101, as viewed in Fig. 1, serves to slide the bar to effect raising movement of the bearing blocks 99-99. Movement of the bar 101 through the bell crank lever 103 is yieldingly opposed by a pair of coil springs 104-104 arranged within the channel beam member 20 at opposite sides of the leaf spring 42. The bar 101 is provided with a depending spring abutment 105, which is in the form of a horizontally disposed plate having downwardly bent spring follower sections at the opposite ends thereof. The plate 105 is secured to the bottom of the bar 101 by means of screws 50 or any other well known securing elements extending through the plate 105 and ferrules 106-106 interposed between the plate 105 and the bar 101. The top wall 23 of the channel beam member 20 is provided with a suitable 55

opening therethrough to accommodate the connecting means between the plate 105 and the bar 101. This opening is of sufficient length to permit the required longitudinal movement of the bar 101 to raise and lower the bearing blocks 98-99. A depending guide pin member 156 is also provided on the bar 101 and works in a guide slot 157 in the wall 23 of the channel beam member 20. This pin member 156, together with the ferrules 106-106, serves to guide the bar 101 in a straight path. The pin member 156 is also in the form of a ferrule secured to the bar 101 by a screw. A washer or plate 158 at the bottom end of the pin member 156 held in position by the screw limits the upward displacement of the corresponding end of the bar 101 by engagement with the wall 23 of the channel beam member 20. The springs 104-104 are interposed between the follower sections of the spring abutment plate 105 and spring abutments 107-107 fixed to the inner side of the top wall 23 of the channel beam member 20. The links 102-102, which support the bearing blocks 98-99, are arranged in pairs at opposite ends of the bar 101. The members 102-102 of each pair of links are arranged on opposite sides of the corresponding bearing block 98 and have their upper ends pivotally connected to said block by a transversely extending pivot pin. The lower ends of the members 102-102 of each pair of links are connected to the bar 101 by a pivot member 108 extending through openings in said links. The links of each pair are arranged at opposite sides of the bar 101, and anti-friction rollers 109-109 are preferably mounted 35 on the pivot 108 and are interposed between the bar 101 and the links 102-102 of said pair. As shown most clearly in Figs. 1, 3a, 3b, 4a, 4b, and 5, the opposite ends of the bar 101 are formed into eyes 110-110, through which the pivot members of the two pairs of links 102-102 and 40 102-102 are engaged. The pivot member 108 at the right-hand end of the bar 101, as seen in Fig. 1, is connected to the bell crank lever 103 by means of a pair of bent links 111-111. As shown most clearly in Fig. 7, the bell crank lever 103 has two spaced arms 112-112 connected by a transverse section 113, which has a projecting rounded lip portion 114 adapted to cooperate with the actuating cam member, as hereinafter 45 pointed out. The bell crank lever 103 is pivotally supported on the channel beam member 20 and the arms 112-112 of said bell crank lever straddle the tubular sleeve 38. The arms of the bell crank lever 103 are provided at their upper ends 50 with ear portions 115-115, through which pivot pins 116-116 extend, which pins are fixed in suitable supports on the channel beam member 20, thus pivotally supporting the bell crank lever 103. The connecting links 111-111 have their 55 right-hand ends, as viewed in Figs. 1, 3b, 4b, and 5, pivotally connected to the lower extremities of the side arms 112-112 of the bell crank lever 103. As shown most clearly in Fig. 7, the opposite ends of the links 111-111 which are connected to the pivot member 108 at the corresponding end of the bar 101 are provided with notches or seats 117-117, which engage over the opposite ends of said pivot member and embrace the corresponding pair of links 102-102. The 60 pivot members 108-108 are preferably headed at opposite ends so as to prevent separation of the parts. The heads of these pivots are preferably in the form of flanged collars 118-118 riveted on reduced end portions of the pivot members 108-108. As shown in Fig. 6, the

notched portions or seats 117-117 of the links 111-111 engage over the collars 118-118 of the corresponding pivot member 108 inwardly of the heads of said collars, the collars thus forming bearing members for the ends of these links. As 5 will be evident, when the bell crank lever 103 is swung in a clockwise direction, as viewed in Figs. 1, 3b, 4b, and 5, the connecting links 111-111 will force the slide 101 to the left against the resistance of the springs 104-104. During this movement, the bearing blocks 98-99 will be raised due to the pairs of links 102-102 and 102-102 being brought toward a vertical position. The bottom roll D will thus be forcibly brought 10 against the top roll C. In order to hold the bottom roll D in its raised position, means is provided for preventing return movement of the bar 101 through the action of the springs 104-104 while the pressure is maintained between the rolls C and D. This means comprises cam projections at opposite sides of the wringer on the top wall 23 of the channel beam member 20. The cam projection at the left-hand side of the wringer, as viewed in Fig. 1, is indicated by 119 and is in the form of a raised section on the 20 wall 23 immediately below the bearing block 98 at that side of the wringer. The cam means at the right-hand side of the wringer, as viewed in Figs. 1 and 8, comprises a pair of transversely aligned, spaced, raised cam sections 120-120. The 30 rollers 109-109 and 109-109 of the pivot members 108-108 of the bar 101 are adapted to ride over the cam sections 119 and 120-120 respectively when the bar 101 is moved to its extreme left-hand position, as viewed in Figs. 4a and 4b, thereby bringing the links 102-102 and 102-102 to a position beyond the vertical and bringing the centers of the antifriction rollers 109-109 beyond the high points of the cam sections 119 and 120-120. The pressure reacting between the 40 rolls C and D of the wringer thus maintains the links 102-102 and 102-102 and the bar 101 locked in position until the pressure is removed, the force of the springs 104-104 being inadequate to pull the rollers 109-109 of the bar 101 and links 102-102 and 102-102 over the high points of the cam sections 119 and 120-120 as long as the pressure is maintained between the rolls C and D. When the pressure is relieved between the rolls C and D by unlocking the frame 45 B from the main frame A, the springs 104-104 will immediately return the bar 101, the links 102-102 and 102-102, and the bearing blocks 98-99, together with the roll D, to the normal position shown in Figs. 1, 3a, 3b, and 5. As will 50 be evident, during this action the pressure transmitted through the links 111-111 will also return the bell crank lever 103 to its normal position.

The drive gearing for the bottom roll D includes a gear element 121 cooperating with a shiftable driving gear element 122 having bevel gear members 123-123 at the upper and lower ends thereof. The shiftable gear element 122 is rotatably journaled in a bushing sleeve 124 fixed 55 within the tubular sleeve 38. The gear element 122 has a splined connection 125 with the shaft 40 hereinbefore referred to, which shaft 40 projects from the vertical standard of the associated washing machine. The gear element 121 has a 60 hollow hub section 126, which is journaled in a bushed bearing opening 127 of the bearing bracket 39. The hollow hub 126 of the gear element 121 is in the form of a socket and has a centrally 65 disposed driving lug 128 projecting from the in- 70

ner wall of said socket. The driving lug 128 is of angular cross section and engages within the coupling sleeve 100 hereinbefore described. As will be evident, the coupling sleeve 100 connects 5 the gear element 121 directly to the shaft 58 of the bottom roll D to rotate this roll. The coupling sleeve 100 preferably has a loose fit on the shaft 58 and the lug 128 of the gear element 121 so that a flexible driving connection is formed 10 and the roll D may be raised and lowered with respect to the gear element 121 without any binding of the parts. The gear element 121 has an annular flangelike portion 129 projecting through the walls of the sleeves 38 and 126, said walls 15 being slotted to accommodate said flange. The annular flange 129 is provided with an annular series of gear teeth, which are adapted to mesh with the teeth of either of the bevel gear members 123—123. The gear element 122 is shifted 20 through movement of the handle or lever 35, which is controlled by the operator. A shifting link 130 operatively connecting the lever 35 with the gear element 122 is employed to communicate the motion from the lever to said gear element. As shown most clearly in Figs. 1, 3b, 4b, 25 5, 10, 11, and 12, the lever 35 is secured to the outer end of a short shaft 131 journaled in the bearing casting 34. To the inner end of the shaft 131 is fixed a cam plate member 132, which 30 cooperates with the bell crank lever 103 hereinbefore referred to. Swinging movement in reverse directions of the lever 35 and the cam plate 132 is limited by spaced stop lugs 159—159 projecting 35 inwardly from the casting 34 and cooperating with flat abutment faces 160—160 on said cam plate. The link 130 has the lower extremity thereof curved, said curved extremity being pivoted to the cam member 132 by a pin 133. The upper end of the link 130 carries a shifting pin 40 134, which extends through said link and has the inner end thereof engaged in an annular groove 135 in the gear element 122. The outer end of the pin 134 is guided for movement in a vertically extending guideway or groove 136 on the inner face of the casting 34. As will be evident, 45 when the lever 35 is swung from the vertical position shown in Fig. 10 to either side as shown in Figs. 11 and 12 respectively, the gear element 122 will be shifted vertically, thereby bringing either 50 of the bevel gear members 123 thereof into operative engagement with the teeth of the gear element 121. The bottom roll D of the wringer will thus be rotated either in right-hand or left-hand direction as desired. In order to stop the operating handle lever 35 and the shiftable gear element 122 in the three different positions of adjustment, namely, the neutral disengaged position of the gear members 123—123, the engaged position of the top gear 123 with the gear element 121, and the engaged position of the bottom bevel gear 123 with the gear element 121, latch means 55 in the form of a spring-pressed plunger 137 cooperating with three seats 138—138—138 in the cam member 132 is provided. The spring-pressed plunger 137, as shown in Figs. 1, 3b, 4b, and 5, is mounted in a socket provided in the casting 34.

In addition to effecting shifting of the gear element 122, operation of the lever or handle 35 also effects raising of the bottom roll D into operative engagement with the top roll C, as hereinbefore described. The cam member 132 has a substantially flat bottom edge face, which has flat surface engagement with the lip 114 of the bell crank lever 103 when the roll D is in the lowered position shown in Fig. 1. This position 60 of the cam member 132 and the bell crank lever 103 is also shown in Fig. 10. When the handle lever 35 is swung in either direction from the vertical position shown in Fig. 10, the cam member 132 will be rotated therewith, thereby actuating the bell crank lever 103 and the connected parts to raise the bottom roll D of the wringer. Upon reference to Figs. 11 and 12, it will be seen that when the handle lever 35 is swung to either side of the vertical position, the cam member 132 10 will depress the cooperating end of the bell crank lever 103 to the same extent, thereby effecting the corresponding lifting movement of the bottom roll D of the wringer.

The lever 35 is further automatically returned 15 to the normal vertical or neutral position when the bottom roll D of the wringer is returned to its lowered position by the action of the springs 104—104 on the slide 101, thereby entirely disconnecting the gear element 122 from the gear 20 element 121 and stopping rotation of the bottom roll D of the wringer. When the pressure between the rolls C and D is removed by unlocking the frame B from the main frame A, as hereinbefore described, the bottom roll D will immediately return to its lowered position through release of the slide 101, which is returned by the action of the springs 104—104, thus rocking the bell crank lever 103 in a contra-clockwise direction, as viewed in Fig. 4b, and swinging the 25 same to the position shown in Fig. 5. During this swinging movement of the bell crank lever 103, the cam member 132 will be forced to return to the normal or neutral position shown in Fig. 10. Upon reference to Figs. 11 and 12, it will be 30 seen that the upward swinging movement of the end of the bell crank lever 103 having the lip 114 will act to restore the cam member 132 and the parts connected therewith to the normal position shown in Fig. 10, regardless of the direction 35 in which the handle 35 has been previously displaced in shifting the gear element 122.

To start my improved wringer, the control lever 35 is swung from the vertical position to one side thereof, thereby bringing one of the bevel 40 gear members 123 into engagement with the gear element 121 and effecting rotation of the bottom roll D. At the same time, the cam member 132 will rock the bell crank lever 103 and raise the roll D into engagement with the roll C, tensioning the leaf spring 42 and holding the rolls C and D in pressure engagement with each other. During the lifting operation of the roll D, the means for returning the operating handle 35 to normal position and restoring the shiftable gear element 45 122 to neutral position, comprising the bell crank lever 103, the connected slide bar 101, and supporting links 102—102 and 102—102, is placed under tension by compressing the springs 104—104. As hereinbefore explained, due to the 50 pressure existing between the top and bottom rolls C and D, the means for returning the lever 35, just mentioned, is held under tension to be immediately released to restore the lever 35 and the shiftable gear member 122 to neutral position when the pressure is removed from the rolls C and D. In case of emergency, the operator pushes on the slide 64, thereby releasing the means for locking the frame B to the main frame A, as shown in Fig. 5, thus removing the pressure 55 from the rolls C and D and effecting release of the restoring means for the handle lever 35. To restore the wringer to operative condition, the frame B is forced down onto the main frame A 60 65 70 75

and the frames are locked together, as hereinbefore described.

In this connection, it is pointed out that when operation of the wringer has once been started by manipulation of the controlling lever 35, the rolls C and D will be held in pressure-exerting relation with respect to each other until the pressure between the rolls is removed by unlocking the frame B from the main frame A. Inasmuch as the pressure between the rolls C and D continues as long as the frame B is locked to the main frame A, the handle lever returning means, including the bar 101 and the bell crank lever 103, will remain locked in the position shown in Figs. 4a and 4b, thereby maintaining the cam-engaging portion of the lever 103 in its depressed position. The operating handle lever 35 is thus free to be rotated to neutral position to disconnect the driving gear means from the roll D and stop operation of the wringer without actuating the bell crank lever 103. Further, the lever 35 may be again swung in either direction from neutral position to operatively connect the driving means with the roll D to again start the wringer without effecting movement of the bell crank lever 103. It will thus be seen that the operating lever 35 is free to effect shifting of the gear element 122 without in any way disturbing the condition of the bottom roll supporting and lifting means as long as the pressure is maintained between the rolls C and D.

I have herein shown and described what I now consider the preferred manner of carrying out my invention, but the same is merely illustrative and I contemplate all changes and modifications that come within the scope of the claims appended hereto.

I claim:

1. In a wringer, the combination with a frame and a pair of cooperating rolls therein; of manually-operated means for projecting one of said rolls against the other roll and displacing the latter; yielding pressure-exerting means acting on said other roll and rendered operative by displacement of said roll to place the rolls under yielding pressure; means for actuating said first named means to retract said projected roll, said actuating means being held inoperative by the pressure exerted between said rolls and becoming operative when said pressure is released and means for separating said rolls to release said pressure and render said last named means operative.

2. In a wringer, the combination with a frame and a pair of cooperating rolls therein; of yielding pressure-exerting means operatively connected to one of said rolls for pressing the same against the other roll; releasable means for buttressing said other roll against the pressure exerted thereon by the yieldingly pressed roll; means for driving said wringer; mechanism for controlling the operation of said driving means; manually operable means independently of the controlling mechanism for releasing said pressure-exerting means from the cooperating roll; and means rendered operative by release of said pressure means for releasing the buttressing means and actuating the controlling mechanism to stop operation of the driving means.

3. In a wringer, the combination with a frame and a pair of cooperating rolls therein; of yielding pressure-exerting means operating on said rolls to press the same together; driving means for said wringer; a manually-operated control member movable in reverse directions for start-

ing and stopping the operation of said driving means; means actuated by movement of said control member in starting direction for projecting one of said rolls against the other roll; manually-controlled means for releasing said pressure-exerting means from operative relation with respect to said rolls, thereby releasing said rolls from pressure; and means rendered operative through release of the pressure between said rolls for retracting said projecting means and actuating said manually-operated control member in reverse direction to stop operation of said driving means.

4. In a wringer, the combination with a frame and a pair of cooperating rolls therein; of yielding pressure-exerting means operating on said rolls to press the same together; driving means for said wringer; a manually-operated controlling member movable to starting and stopping positions for respectively starting and stopping the operation of the driving means; means actuated by movement of said controlling member to starting position for projecting one of said rolls against the other roll; means for releasing said pressure-exerting means from operative pressure-exerting relation with respect to said rolls; and means held under tension by the pressure exerted between said rolls and released by removal of said pressure for retracting said projecting means and returning said controlling member to stopping position.

5. In a wringer, the combination with a frame and a pair of cooperating rolls therein; of yielding pressure-exerting means operating on said rolls to force the same together; driving means for said wringer; a manually-operated controlling member movable to starting and stopping positions for respectively starting and stopping operation of the driving means; means held under tension by the pressure between said rolls for returning said controlling member from starting to stopping position; means forming a part of the returning means and operated by movement of said controlling member to starting position for projecting one of said rolls against the other; and manually-controlled means for releasing said pressure-exerting means from operative relation with respect to said rolls, thereby relieving the pressure between said rolls and releasing said returning means to restore the controlling member to operative position.

6. In a wringer, the combination with a frame and a pair of cooperating rolls therein; of means for yieldingly pressing one of said rolls toward the other roll; means movable in one direction for projecting said other roll against the yieldingly pressed roll, and movable in a reverse direction to retract said projected roll; driving means for rotating one of said rolls; a manually-operated movable controlling member for starting and stopping rotation of said driving means; means fixed to and movable with said manually-operated member and engaging said movable means when said manually-operated member is moved to starting position for actuating said movable means in a direction to project the cooperating roll; means for releasing said rolls from the pressure of said yielding means; and means rendered operative by removal of said pressure for actuating said movable means in reverse direction to return the manually-operated member to stopping position.

7. In a wringer, the combination with a frame and a pair of cooperating rolls therein; of yielding pressure-exerting means for pressing one of

5 said rolls toward the other roll; reciprocating means for moving said other roll toward and away from said yieldingly pressed roll; a manually-operated actuating member for operating said reciprocating means in one direction to project said other roll against the yieldingly pressed roll; means energized by operation of said reciprocating means in said direction for actuating the reciprocating means in a reverse direction and 10 turning said actuating member; stop means rendered effective by the pressure on said rolls for holding said reciprocating means against movement in said reverse direction; and means for releasing said yieldingly pressed roll from the 15 pressure of said yielding means, thereby releasing said stop means and permitting operation of the reciprocating means by said energized means.

8. In a wringer, the combination with a frame and a pair of cooperating rolls therein; of yielding pressure-exerting means for pressing one of said rolls toward the other roll; reciprocating means for moving said other roll toward and away from said yieldingly pressed roll; rotating driving means; shiftable means movable to one position 25 for connecting one of said rolls to said rotating means and movable to another position for disconnecting the same therefrom; a movable control member for actuating said shiftable means; means actuated by said control member in moving said shiftable means to said first named position to operate said reciprocating means in a direction to project said other roll against the yieldingly pressed roll; and means energized by operation of said reciprocating means in said last 30 named direction for moving said reciprocating means in a reverse direction and moving the control member to disengage said shiftable means.

9. In a wringer, the combination with a frame and a pair of cooperating rolls therein; of yielding pressure-exerting means for pressing one of said rolls toward the other roll; reciprocating means for moving said other roll toward and away from said yieldingly pressed roll; rotating driving means; shiftable means movable to one 45 position for connecting one of said rolls to said rotating means and movable to another position for disconnecting the same therefrom; a movable control member for actuating said shiftable means; means actuated by said control member in moving said shiftable means to said first named position to operate said reciprocating means in a direction to project said other roll against the yieldingly pressed roll; means energized by operation of said reciprocating means in said last 50 named direction for moving said reciprocating means in a reverse direction and moving the control member to disengage said shiftable means; stop means rendered effective by the pressure on said rolls for holding said reciprocating means against movement in said reverse direction; and means for disconnecting said yieldingly pressed roll from the pressure-exerting means and releasing said stop means to permit operation of said reciprocating means by said energized means.

10. In a wringer, the combination with a frame and top and bottom rolls therein; of yielding pressure-exerting means operatively connected to said top roll and opposing upward displacement of the same; manually-operated means for raising said bottom roll to project the same against the top roll; means held against operation by the pressure between said rolls for returning said bottom roll to lowered position; and means 70 for disconnecting the pressure means from said

top roll to relieve the pressure between said rolls and permit operation of said returning means.

11. In a wringer, the combination with a frame and top and bottom rolls therein; of driving means for one of said rolls; power-transmitting means; a movable controlling member for connecting the driving means to and disconnecting the same from the power-transmitting means; yielding pressure means opposing upward displacement of the top roll; means operated by 10 movement of the controlling member in connecting the driving means with the power-transmitting means for raising the bottom roll to project the same against the top roll; means held against operation by the pressure between said rolls for returning said raising means and the bottom roll to lowered position; and means for disconnecting the pressure means from the top roll to release the pressure on said top roll and free the returning means to effect lowering of the bottom roll. 15

12. In a wringer, the combination with a frame and top and bottom rolls therein; of driving means for one of said rolls; rotating power-transmitting means; a movable controlling member 25 for connecting the driving means to the power means and disconnecting the same therefrom; pressure-exerting means yieldingly opposing upward displacement of the top roll; means operated by movement of the controlling member in connecting the driving means to the power means for raising said bottom roll; means held against operation by the pressure between said rolls for returning the raising means to lowered position and actuating the controlling member to disconnect the power means from the driving means; and means for disconnecting the pressure means from said top roll and freeing said returning 30 means to lower said raising means and actuate said controlling member. 35

13. In a wringer, the combination with a frame and top and bottom rolls therein; of driving means for one of said rolls; rotating power means; means for connecting said driving means to the power means and disconnecting the same therefrom; a movable controlling member for 45 actuating said connecting means to start and stop rotation of the driving means; pressure-exerting means connected to said top roll and yieldingly opposing upward displacement of the same; means actuated by movement of said controlling member to starting position for raising said bottom roll to project the same against said top roll; and means automatically thrown into action by operation of said disconnecting means for lowering said bottom roll and moving the 50 controlling member to stopping position. 55

14. In a wringer, the combination with a frame and top and bottom rolls therein; of yielding pressure-exerting means opposing upward displacement of the top roll; a support below said 60 bottom roll; carrier means in which said bottom roll is rotatably supported; means for guiding said carrier means for vertical movement; depending arms pivoted to the carrier means and buttressed against said support; and means for 65 displacing said arms along said support to raise and lower the bottom roll.

15. In a wringer, the combination with a frame and top and bottom rolls therein; of yielding pressure-exerting means opposing upward displacement of the top roll; a support below said 70 bottom roll; carrier means in which said bottom roll is rotatably mounted; means for guiding said carrier means for vertical movement; depending arms pivoted on said carrier means and but- 75

- tressed at their lower ends against said support, said arms being normally inclined; and means for displacing the lower ends of said arms to raise said bottom roll and project the same against said top roll and bring said rolls into pressure-exerting relation.
16. In a wringer, the combination with a frame and top and bottom rolls therein; of yielding pressure-exerting means opposing upward displacement of the top roll; a support below said bottom roll; carrier means in which said bottom roll is rotatably mounted; means for guiding said carrier means for vertical movement; depending arms pivoted on said carrier means and but-tressed at their lower ends against said support, said arms being normally inclined; means for displacing the lower ends of said arms to raise said bottom roll and project the same against said top roll and bring said rolls into pressure-exerting relation; and spring means for displacing the lower ends of said arms in a reverse direction to lower said bottom roll.
17. In a wringer, the combination with a frame and top and bottom rolls therein; of yielding pressure-exerting means connected to said top roll for opposing upward displacement of the same; a support beneath said bottom roll; carriers in which said bottom roll is rotatably supported; means for guiding said carriers for vertical movement; pivoted supporting legs on said carriers bearing on said support, said legs being normally inclined; means for displacing the lower ends of said legs through vertical position to raise said carriers and project the bottom roll to pressure-exerting position with respect to the top roll, whereby the pressure between said rolls holds said legs against return movement; means for disconnecting the pressure-exerting means from said top roll to remove the pressure on said rolls; and spring means acting to return said legs to normal position upon removal of said pressure.
18. In a wringer, the combination with a frame and top and bottom rolls therein; of yielding pressure-exerting means connected to said top roll opposing upward movement of the same; a support beneath said bottom roll; carriers in which said bottom roll is rotatably mounted; means for guiding said carriers for vertical movement; pivoted supporting legs on each of said carriers resting on said support, said legs being normally inclined; means connecting the lower ends of said legs for movement in unison; means for actuating said connecting means in one direction to raise said carriers and project said bottom roll against the top roll and lift said top roll against the pressure-exerting means; means energized by movement of said connecting means in said direction adapted to move the connecting means in a reverse direction to lower said bottom roll; means cooperating with said legs for holding the same against movement when said rolls are operating under pressure, thereby maintaining said energized means inoperative; and means for disconnecting the pressure-exerting means from the top roll to relieve the pressure between said rolls to thereby release said legs and render said energized means operative to move the connecting means in a reverse direction and lower said bottom roll.
19. In a wringer, the combination with a frame and top and bottom rolls therein; of means for raising and lowering said bottom roll; means for rotating one of said rolls; a movable controlling lever for starting and stopping operation of said rotating means; a cam member movable in uni-

son with said controlling lever; motion-transmitting means between said cam member and said first named means, said motion-transmitting means being moved in one direction by said cam member through movement of said lever to starting position for actuating said first named means to raise the bottom roll and project the same against the top roll; and means energized by movement of said motion-transmitting means in said direction for actuating the motion-transmitting means in reverse direction and operating the cam member to return the controlling lever to stopping position.

20. In a wringer, the combination with a frame and top and bottom rolls therein; of yielding pressure-exerting means connected to said top roll for pressing the same toward said bottom roll; driving means for one of said rolls; gear means for rotating said driving means; an oscillating cam member; a fixed control lever on said cam member; means operatively connecting said lever to said gear means for starting and stopping rotation of said driving means; means for raising and lowering the bottom roll; a movable actuating member interposed between said cam member and the raising and lowering means and moved in one direction by said cam member upon movement of said lever to starting position to actuate said raising and lowering means and project the bottom roll against the top roll and force the latter against said pressure means; means energized by movement of said actuating means in said direction for moving the latter in a reverse direction and actuating the cam member to restore the lever to stopping position, said energized means being held against operation by the pressure between said rolls; and means for disconnecting the pressure-exerting means from said top roll and relieving the pressure between said rolls to permit operation of said energized means.

21. In a wringer, the combination with a frame and top and bottom rolls therein; of a rotary driving member for one of said rolls; gearing for rotating said driving member; a rocking controlling lever operatively connected to said gearing for starting and stopping rotation of the driving member; a cam member fixed to and rockable with said lever; a bell crank lever rocked in one direction by said cam member through movement of the controlling lever to starting position; means actuated by rocking movement of the bell crank lever in said direction for raising said bottom roll to project the same against the top roll; and means for actuating said last named means to lowered position and rocking said bell crank lever in a reverse direction to operate the cam member and restore the controlling lever to stopping position.

22. In a wringer, the combination with a frame and top and bottom rolls therein; of rotary driving means for one of said rolls; power-transmitting means; shiftable gear means for connecting said power-transmitting means to the driving means for rotating the latter in reverse directions; an oscillatory control lever for said shiftable gear means, said lever being movable to two extreme positions to effect rotation of said driving means in respective reverse directions, and movable to an intermediate neutral position to disengage said shiftable gear means and stop rotation of the driving means; a cam member fixed to said lever and oscillatable therewith; a motion-transmitting element movable in reverse directions, said motion-transmitting element be-

- ing engaged by said cam member and moved in one direction upon movement of the control lever from neutral position to either of said extreme positions, said motion-transmitting element when 5 moved in a reverse direction engaging the cam member to oscillate the same and restore the lever to neutral position; means actuated by movement of said motion-transmitting element by said cam member for raising the bottom roll to project the same against the top roll to lift the latter; yielding pressure-exerting means connected to said top roll and opposing lifting of the same; means for disconnecting the pressure-exerting means from said top roll; and means automatically actuated upon said pressure means being disconnected for lowering said bottom roll and actuating the motion-transmitting means in said reverse direction to restore the control lever to neutral position. 10
23. In a wringer, the combination with top and bottom rolls; of a main frame; yielding pressure-exerting means carried by said main frame; an auxiliary frame adapted to be associated with the main frame; releasable locking means for connecting said auxiliary frame to the pressure-exerting means; means mounted on said main frame for raising said bottom roll to project the same against the top roll and lift the latter against the resistance of said pressure means; 15 and means for releasing said locking means to disconnect the auxiliary frame from the pressure-exerting means and relieve the pressure between said rolls. 20
24. In a wringer, the combination with top and bottom rolls; of a main frame; an auxiliary top frame; depending struts on said top frame in which the top roll is journaled; connecting bars at opposite sides of the main frame; releasable means on the auxiliary frame for locking the same to said connecting bars; a spring on said main frame anchored to the connecting bars and exerting a downward pull thereon; raising and lowering means on said main frame for said bottom roll; means for actuating said last named 25 means for raising said bottom roll and projecting the same against the top roll; and means for releasing said locking means, thereby disconnecting said auxiliary frame from the main frame to permit lifting of said top roll. 30
25. In a wringer, the combination with top and bottom rolls; of a bottom frame; spring tension means on said bottom frame; connecting bars anchored to said spring means; an auxiliary top frame carrying said top roll; releasable means for locking said auxiliary frame to the connecting 35 bars; means on said bottom frame for supporting the bottom roll in pressure-exerting relation with respect to the top roll; means for releasing said locking means to disconnect the auxiliary frame from the bottom frame and relieving the pressure between said rolls; and means for lowering said supporting means and said bottom roll to provide clearance for said top roll in replacing the auxiliary frame on the bottom frame and locking said frames together. 5
26. In a wringer, the combination with a frame and top and bottom rolls therein; of means for raising said bottom roll into engagement with the top roll including a horizontally movable slide, upstanding pivoted links on said slide supporting said bottom roll; means for rotating one of said rolls; a movable control member for starting and stopping the rotating means; and means adapted to be actuated, incident to movement of the control member (in a direction for rotating said last mentioned roll) for reciprocating the slide to raise the bottom roll into cooperating relation 10 with the upper roll. 15
27. In a wringer, the combination with a frame and top and bottom rolls therein; of means for raising said bottom roll into engagement with the top roll including a horizontally movable slide, upstanding pivoted links on said slide supporting said bottom roll; means for rotating one 20 of said rolls; a movable control member for starting and stopping the rotating means; means adapted to be actuated, incident to movement of the control member (in a direction for rotating said last mentioned roll) for reciprocating the slide to raise the bottom roll into cooperating relation 25 with the upper roll; and releasable means for maintaining said slide actuating means 30 in position for holding said lower roll in raised position, said raising means being non-responsive to movement of the control member in a direction for stopping rotation of the driving roll. 35
28. In a wringer, the combination with top and bottom rolls; of a main frame; yielding pressure-exerting means carried by said main frame; an auxiliary frame adapted to be associated with the main frame; releasable locking means for connecting said auxiliary frame to the pressure-exerting means; means mounted on said main frame for raising said bottom roll to project the same against the top roll and lift the latter against the resistance of said pressure means; 40 means for releasing said locking means to disconnect the auxiliary frame from the pressure-exerting means and relieving the pressure said rolls; and spring means rendered operative upon release of said locking means for returning said raising means to original position for lowering 45 said bottom roll. 50

SIMON E. SCHROEDER.

CERTIFICATE OF CORRECTION.

Patent No. 2,209,422.

July 30, 1940.

SIMON E. SCHROEDER.

It is hereby certified that error appears in the printed specification of the above numbered patent requiring correction as follows: Page 2, second column, line 42, for the reference numerals "140-740" read --140-140--; page 5, second column, line 48, for "bearings" read --bearing--; line 70, for "screws" read --screws--; page 7, second column, line 15, for "automatically" read --automatically--; page 11, second column, line 52, claim 28, after "pressure" insert --between--; and that the said Letters Patent should be read with this correction therein that the same may conform to the record of the case in the Patent Office.

Signed and sealed this 29th day of October, A. D. 1940.

Henry Van Arsdale,
Acting Commissioner of Patents.
